SHOE AND METHOD OF MAKING THE SAME

Walter P. Field, Brockton, Mass.

Application February 12, 1936, Serial No. 63,498

27 Claims. (Cl. 12—142)

This invention relates to the manufacture of shoes, and more especially to an improved boot or shoe and to a process for making the same.

Heretofore, in the manufacture of what are termed "cemented" shoes, that is, shoes in which the outer sole is secured to the upper by cement alone and without the use of stitching, no practical method has been devised for producing a shoe of the welt type. The manufacture of cemented shoes has been almost exclusively confined to the production of women's shoes and to those of a type in which the outer sole is of leather and does not extend beyond the upper. This has been due mainly to the difficulties inherent in securing a durable and wear-resisting bond between the upper and the outer sole where cement alone is the adhesive agent.

So far as I am informed, the use of the cementing process has, heretofore, been confined to the attachment of leather outer soles to shoe uppers and no practical method has been evolved for using, in a cemented shoe, an outer sole of rubber or similar composition. It is difficult, if not impossible, to cement material like rubber composition to leather and to secure a firm and permanent bond between the two, and the difficulty of accomplishing this end explains the lack on the market of cemented shoes having composition soles.

The main object of my invention is the provision of a cemented shoe having, both inside and outside, the appearance of a genuine Goodyear welt shoe and having the durability and wearing qualities of a shoe of that character, and the provision of a method for making the same.

Another principal object of my invention is the provision of a cemented shoe of the welt type, which may have either a leather outer sole or one of rubber composition or similar material.

One of the specific objects of my invention is the provision in a cemented shoe of the welt type, of means for securing a permanent and durable attachment of the outer sole to the shoe upper, including a cement-carrying bonding member permanently attached to the outer sole, which may be cemented to the shoe upper and inner sole for insuring a permanent and lasting adhesion between those parts of the shoe.

Another important object of the invention is the provision in a cemented shoe of the welt type, of a cement-carrying bonding member which may be used with an outer sole either of leather or rubber composition or of similar material, to secure a permanent and durable bond between the shoe upper and the outer sole.

A further object of the invention is the provision of a shoe of the welt type with either a leather or a composition outer sole, which is simple in construction and which can be produced at an extremely low cost.

An additional object of the invention is the provision of a simple method for making shoes of the foregoing description which eliminates many of the steps heretofore considered necessary in the making of welt shoes and which materially shortens the time consumed in the production of the shoes.

Other objects of the invention will be more particularly set forth and described hereinafter.

My invention contemplates a cemented shoe and a method for making the same, in which there is permanently attached to the outer sole, a cement-carrying bonding member, adapted to be cemented to the shoe upper to produce a durable and wear-resisting bond between those two parts. Preferably, this bonding member comprises a strip of suitable fabric, such as canvas or duck, which is fastened to and made a part of the welt, the strip extending inwardly from the inner edge of the welt. The welt extends around the margin of the fore-part of the outer sole from the heel seat in the usual manner and is permanently attached, either by cement or stitching, to the outer sole, so that the outer sole, welt and bonding member are thereafter handled as a unit in cementing the outer sole to the shoe upper.

A fabric strip of this character constitutes an especially good bonding member in a cementing process, because the construction of the fabric permits a cement applied thereto, such as pyroxylin, to penetrate the interstices between the threads of the fabric, so that when it is cemented to the roughened surfaces of the shoe upper, it constitutes a most effective and efficient bonding medium and produces a durable and permanent adhesion between the outer sole and the upper.

In carrying out my invention, the fabric strip is attached along its outer longitudinal edge to the welt and the welt is fastened to the outer sole in any suitable manner, either by stitching or cementing, dependent upon the materials used for the welt and the sole. When both the outer sole and the welt are of leather, these two parts may be attached by cementing and the fabric strip may be either cemented or stitched to the welt. However, if a rubber composition welt is used with a leather sole, stitching will have to be utilized for attaching the fabric strip to the welt and for attaching the welt to the outer sole, be-

cause it is impossible to get, with the use of cement, anything more than a temporary bond between fabric or leather on the one hand, and rubber composition on the other hand. In the 5 case of a rubber composition sole having a welt of the same material, the two may be efficiently attached by the use of cement, but the fabric strip will have to be stitched to the welt, or incorporated with the welt in the vulcanizing 10 process when it is made in order to secure a permanent bond between the two.

In the preferred form of the invention, however, and in order to preserve the appearance of a welt shoe, the welt is stitched to the outer sole adjacent its outer edge by the usual welt lock stitching and this stitching may be relied upon for fastening the fabric strip to the welt. Whatever materials are used for the welt and the outer sole, my invention contemplates the 15 permanent attachment of the bonding strip to the welt, and the welt to the outer sole, by such means as may be adequate to accomplish this end.

I have found that the use of such a bonding member as above described for cementing an 20 outer sole to a shoe upper gives astonishing results so far as the permanency and durability of the bond between those parts is concerned. I am aware that certain types of shoes, having close-trimmed leather soles, have heretofore been 25 made by the cementing process, but this has been largely confined to the manufacture of light shoes for women. My invention, however, not only can be applied to the manufacture of women's shoes of the foregoing type with improved results, but it extends that process to the 30 making of shoes of heavier construction adapted for men and to shoes having an extension sole. In short, by the use of a bonding member in accordance with my invention, a cemented shoe of the welt type, having either a leather or a composition outer sole and having the appearance and durability of high-priced 35 shoes, can be made at an extremely low cost.

In the accompanying drawings illustrating my 40 invention, Figure 1 is a side elevation of a man's shoe constructed in accordance with my invention;

Fig. 2 is a bottom plan view on an enlarged 45 scale of a lasted upper and inner sole, in which the upper is cemented to the inner sole with lasting tacks shown for holding the toe portion of the upper in place during the setting of the cement and with side stapling;

Fig. 3 is a similar view of the lasted upper 50 with the lasting tacks at the toe removed and the surplus material trimmed off, with the edges of the upper ready to be roughened for receiving the cement;

Fig. 4 is a plan view of the inner face of an 55 outer sole having a welt attached thereto, the welt being shown as provided with an inwardly extending bonding strip of fabric and secured to the welt at its outer edge;

Fig. 5 is a cross-sectional view on line 5-5 in 60 Fig. 4;

Fig. 6 is a cross-sectional view similar to Figure 65 5, of a modified form of outer sole and welt unit, in which the bonding strip is attached to the welt by insertion within a channel formed in the welt;

Fig. 7 is a cross-sectional view through the 70 vamp portion of a preferred form of shoe constructed in accordance with my invention;

Fig. 8 is a similar view of a modified form of 75 shoe, utilizing the outer sole unit shown in Fig. 6;

Fig. 9 is a plan view of a section of weltling, provided with a corrugated top face; and

Fig. 10 is an outer side elevation of the same. In the drawings, my invention is shown as exemplified in a man's oxford shoe of the welt 5 type, but it is to be understood that this is merely for the purpose of illustration and that the invention is also applicable to the manufacture of women's and children's shoes, and, generally, to the manufacture of all kinds of foot- 10 wear coming under the generic term "shoe". As shown, the shoe comprises an upper designated generally as 10, an inner sole 12, an outer sole 14, and a heel 16. The upper, which may be made in any suitable manner, is shown as comprising outer parts consisting of a pair of quarters 18, a vamp 20, and a tip 22, and inner parts include a lining 24, a box toe 26, and a heel counter 28. The outer sole 14 is provided with a welt 30 fastened thereto, and to the welt is 20 attached a bonding strip 32 of any material which is adapted for carrying a suitable adhesive for fastening the outer sole to the upper.

In the method of making a shoe according to my invention, the shoe upper is first prepared 25 in the usual manner by assembling and fastening the various parts thereof in their proper relations, after which the inner sole 12 is tacked to the last and the prepared shoe upper is fitted over the last ready for the pulling-over operation. The upper is then lasted, and this may be done by any suitable McKay method of lasting, either full cement lasting, step-by-step nail lasting, or staple lasting. A combination of the cement and staple methods is preferred for the 30 lasting operation, and, in carrying this out, the bottom edges and the margin of the outer face of the inner sole are coated with any suitable cement, and the edges of the upper are then pulled over and adhesively fastened to the inner 40 sole, and the sides of the upper are staple-lasted with staples 34 to the inner sole by the well-known Littleway process. In the latter process, the staples are of light construction and are clenched within the inner sole without going 45 through and appearing on its inner surface. Around the toe, the pulled-over edges of the upper may be temporarily held in place to permit the cement to set, by pull-over tacks 36 inserted in the toe portion of the last. The edges 50 of the upper around the heel are preferably lasted by the use of permanent tacks 38, but these edges may be lasted by adhesive alone if desired. In Figure 2, there is shown a lasted upper in its condition at the conclusion of the 55 lasting operation.

After the cement has thoroughly dried or set, the pull-over tacks 36 are withdrawn and the surplus material of the upper, including the box toe and lining around the toe portion of the last, 60 are trimmed off to provide a smooth, flat surface, as shown in Figure 3. The exposed edges of the outer leather parts of the shoe upper are then scoured or roughened in preparation for application of the cement for affixing the outer sole 65 thereto.

Simultaneously with the preparation of the lasted upper, my method includes the preparation 70 of an outer sole unit, comprising the outer sole 14, the welt 30, and a suitable bonding strip 70 32 for attaching, by the use of cement, the outer sole unit to the shoe upper. In the preparation of this unit, the outer sole is died out of suitable material to the exact form and dimension required by the last. The died-out sole is then 75

run through a splitting machine to fit it and secure uniform thickness and a roughened inner face. The welt is then applied around the margin of the forepart of the sole from the heel breast on one side to the heel breast on the other side and fastened to the outer sole by any suitable means.

Preferably, the welt 30 is previously prepared with a bonding strip 32 attached along its outer edge to it, so that the welt and bonding strip may be attached as a unit to the outer sole. The main portion of the bonding strip extends inwardly from the inner edge of the welt and is free for the greater portion of its width, so that a cement may be applied to both sides of the strip. The free portion of the strip should be sufficiently wide to insure a permanent bond between the bonding strip and the shoe upper when the two are cemented together and I have found that a bonding strip with a free portion of approximately one-half to five-eighths of an inch will attain this end. The bonding strip may be made of any material suitable for carrying an adhesive, but preferably, a fabric such as duck or canvas makes the best bonding strip, because its woven construction permits the adhesive to permeate the strip, and, when set, to become anchored in and among the threads. The bonding strip may be made in strip form or it may be died out in horse-shoe form.

The welt itself may be of various forms and the bonding strip may be attached to it in different ways, dependent somewhat upon the material of which the welt is made. Preferably, the welt 30 is a narrow strip of material having parallel top and bottom faces with a beveled inner edge. The welt may have its bottom face provided with a shallow recess extending from its inner edge to adjacent its outer edge, as shown in Figure 5, or it may be channeled inwardly from its inner edge and parallel with its bottom face to a line adjacent its outer edge, as illustrated in Figure 6. In the first case, the outer edge of the bonding strip is inserted in the recess, and, in the latter case, it is inserted in the channel, and, in both cases, is fastened therein, preferably by the use of cement.

In attaching the welt carrying the bonding strip to the outer sole, I prefer to use a single line of welt stitching 40, which is so located as to pass through the outer edge of the bonding strip and thereby permanently fasten together the welt, the bonding strip and the outer sole. The stitching 40 may be either of the well-known lock or chain forms. When the lock stitching is used, it may be left exposed on the outer face of the outer sole, or it may be laid in a narrow channel cut in the outer face of the sole and covered by a turned-back portion; but in the case of chain stitching, it is preferably to form a channel in the outer face of the sole for concealing it.

When the outer sole and the welt are both of leather, the stitching 40 may, if desired, be omitted, because a permanent bond can be secured between the welt and bonding strip, and the welt and outer sole, by the use of cement alone; but, when either the welt or the outer sole, or both of them, are of rubber composition or similar material, the stitching 40 is required to permanently fasten these parts together. In the preparation of a welt of rubber composition or similar material, the use of cement for fastening the bonding strip to the welt is sufficient for insuring temporary fastening of the

welt and bonding strip together; but when the outer sole welted unit is prepared, the stitching 40 is required for a permanent bond between the parts.

When both the outer sole and the welt are of rubber composition, the bonding strip may be permanently fastened to the welt by being incorporated in it during the molding and vulcanizing process, so that it becomes an integral part of the welt, and, in such case, the welt and the outer sole being of similar material, they may be permanently fastened together by the use of cement. With such a construction, the welt stitching may be omitted if desired.

After the shoe upper and the outer welted sole unit have been prepared, the bottom edges of the lasted upper from the heel breast forward and the bonding strip are coated with any suitable cement, such as pyroxylin. Preferably, these parts are given a first coating of cement, the bonding strip being coated on both sides, which coating is allowed to dry, after which either a second coating of the cement, or, in the case of pyroxylin, a coating of an activator is applied to the first coating, and the outer sole unit is immediately spotted on the shoe upper and suitable pressure is applied to the parts to cause a complete adhesion between the outer sole unit and the lasted upper. This pressure is maintained until the cement has finally set.

As a result, a permanent bond is effected between the bonding strip and the shoe upper and, to some extent, there is a bond between the lower surface of the bonding strip and the outer sole, the amount of this bond being somewhat dependent upon the material of which the outer sole is made. With a leather outer sole, the bond will be as complete and as firm as between the bonding strip and the upper; but with a composition sole, the bond between the strip and the outer sole is of less permanence. After the shoe is released from the pressure, the heel portion of the outer sole is then nailed around the heel in the usual manner, after which the heel may be applied thereto. The edges of the outer sole and welt are then trimmed and set. This operation may, however, when the sole and welt are fastened together by stitching, be performed before the welted sole unit is adhesively fastened to the shoe upper. After this, the shoe may be subjected to any further finishing operations required.

The shoe may be made with or without a filler. In Figure 7 of the drawings, it is shown as made without a filler; and in Figure 8, with a filler 42. Any suitable filler may be used, such as a thin, firm felt filler, which I have found gives the best results, and this filler is applied to the shoe upper after it is lasted and before the cement is applied to its bottom edges.

Some of the important advantages of my invention are that it eliminates many of the costly operations now involved in producing a genuine Goodyear welt shoe and simplifies the process to an amazing extent; that it eliminates the rough inside of the McKay made shoe, whether produced by lock stitching or other variations of the McKay system; and that it further eliminates the stiff midsole, which is characteristic of the McKay, welt and nailed shoes, and, consequently, results in producing a more flexible and resilient shoe than any produced by either of the systems mentioned above. In short, my invention permits the production of a shoe having the appearance, both inside and out, the durability and

wearing qualities, and other advantages of high-grade Goodyear welt shoes at a production cost of cheap shoes.

One of the advantages in using a welt of rubber composition, or similar moldable material, is that the exposed face of the welt may be provided with transverse corrugations 44 more closely simulating the appearance of a Goodyear welt, as shown in Figure 9, which corrugations 10 may be formed in the molding process and, therefore, are permanent and are not affected by wear. The same indentations in a leather welt disappear with the absorption of moisture by the leather, so that the welt in time becomes comparatively smooth.

Another important advantage which flows from the use of my invention in shoes having rubber composition soles is that the soles may be made of a color to harmonize with the color of the shoe upper. During the past few years, there has been a growing tendency in the shoe manufacturing industry to produce shoes having uppers of all shades of color. This tendency, which has heretofore been duly confined to women's shoes, is now spreading to men's shoes, and it not only includes uppers of different colors, but also combinations of different colors in the same shoe. Attempts have heretofore been made to carry out these color schemes in shoes having leather soles by painting the soles and welts, if provided with welts, or by coating them with a veneer. This has not proved satisfactory, however, because the paint or veneer soon wears off and disappears. Rubber composition, however, can be made in any color, and soles and welts of this material can be made to match exactly the color of the shoe upper, or can be made of a different color in harmony with the color of the shoe upper, and the color of the sole and welt is permanent. The coloring of rubber composition is done in the mixing and molding of that material, so that there is no appreciable increase in its cost, whereas, the coloring of a leather sole and a leather welt involves additional operations which increase the cost of the shoe.

Although I have described herein, as a part of my invention, the attachment of the welt to the outer sole by stitching or by cement, yet it may 50 be accomplished by other means, such, for instance, as stapling the welt to the outer sole by staples set in a channel formed in the outer surface of the sole and clenched invisibly in the welt. This form of construction may be found of advantage in very cheap shoes made in accordance 55 with my invention.

It is to be understood that my invention is not to be limited to the precise forms herein shown and described, since it may be embodied 60 in various other forms, all within the scope of the following claims.

What I claim is:

1. A cemented shoe comprising an upper, an inner sole, an outer sole having a welt fastened 65 thereto and a bonding strip attached along its outer edge to said welt and cemented to the bottom edges of said upper for attaching said outer sole to said upper.

2. A cemented shoe comprising an upper, an 70 inner sole, an outer sole having a welt permanently attached thereto and a bonding strip of fabric permanently attached along its outer edge to said welt and cemented to the bottom edges of said upper for attaching said outer sole permanently to said upper.

3. A cemented shoe comprising an upper, an inner sole, an outer sole, a welt attached to said outer sole and a bonding strip of fabric permanently attached along its outer edge to the inner edge of said welt and cemented to the bottom edges of said upper for attaching said outer sole permanently to said upper.

4. A cemented shoe comprising an inner sole, an upper having its bottom edges lasted inwardly over the lower surface of said insole, an outer sole, a welt attached to said outer sole and a strip of fabric secured along its outer edge to said welt and cemented to the bottom edges of said upper for attaching said outer sole permanently to said upper.

5. A shoe comprising an inner sole, an upper having its bottom edges lasted inwardly over the lower marginal surface of said insole and cemented thereto, an outer sole, a welt attached to said outer sole and a strip of fabric secured 20 along its outer edge to said welt, the free inner portion of said strip being cemented to the bottom edges of said upper for attaching said outer sole permanently to said upper.

6. A shoe comprising an inner sole, an upper having its bottom edges lasted inwardly over the lower marginal surface of said insole and attached thereto, an outer sole, a welt attached to said outer sole and a strip of fabric secured along 30 its outer edge to said welt and extending inwardly, said strip being cemented to the bottom edges of said upper for attaching said outer sole permanently to said upper.

7. A shoe comprising an inner sole, an upper having its bottom edges lasted inwardly over the lower surface of said insole, an outer sole, a welt fastened to said outer sole by a line of lock stitching and a bonding strip having its outer edge intermediate said welt and said outer sole and fastened therein by said lock stitching, the inner 40 longitudinal portion of said strip being cemented to the bottom edges of said upper and said inner sole for attaching said outer sole permanently to said upper.

8. A shoe comprising an inner sole, an upper having its bottom edges turned inwardly over the marginal outer surface of said insole and fastened thereto, an outer sole, a welt attached thereto, said welt having its inner edge channeled parallel with its bottom face, and a strip of fabric 50 having its outer edge inserted in said channel and secured therein, the remaining inner portion of said strip being cemented to the bottom edges of said upper and inner sole for fastening said outer sole to said upper.

9. A shoe comprising an inner sole, an upper having its bottom edges turned inwardly over the marginal outer surface of said insole and fastened thereto, an outer sole, a welt attached thereto and a strip of fabric having its outer edge 60 inserted between the inner edge of said welt and said outer sole and fastened therein, the remaining inner portion of said strip being cemented to the bottom edges of said upper and inner sole for fastening said outer sole to said upper.

10. A shoe comprising an inner sole, an upper having its bottom edges turned inwardly over the marginal outer surface of said insole and fastened thereto, an outer sole, a welt attached thereto by a line of lock stitching, said welt having its inner edge channeled parallel with its bottom face, and a strip of fabric having its outer edge inserted in said channel and secured therein by said line of lock stitching, the remaining inner portion of said strip being cemented to the bot- 70 75

tom edges of said upper and inner sole for fastening said outer sole to said upper.

11. A shoe comprising an inner sole, an upper having its bottom edges turned inwardly over the marginal outer surface of said insole and fastened thereto, an outer sole, a welt attached thereto by a line of lock stitching, said welt having its bottom face provided with a shallow recess extending from its inner edge to adjacent its outer edge, and a strip of fabric having its outer edge inserted in said recess and secured therein by said line of lock stitching, the remaining inner portion of said strip being cemented to the bottom edges of said upper and inner sole for fastening said outer sole to said upper.

12. The herein described method for making a cemented shoe consisting in preparing a lasted upper and an outer sole having a welt attached thereto and a bonding strip of cement carrying material attached along its outer edge to said welt, then applying cement to the bottom edges of said lasted upper and to said bonding strip and, finally, while said cement is in a tacky condition, applying pressure to said outer sole to cement said bonding strip to said lasted upper to permanently attach said sole thereto.

13. The herein described method for making a cemented shoe consisting in preparing a lasted upper and an outer sole having a welt attached thereto and a bonding strip of suitable cement carrying material permanently attached along its outer edge to said welt, then applying cement to the bottom edges of said lasted upper and to said bonding strip and, finally, while said cement is in a tacky condition, applying pressure to said outer sole to cement said bonding strip to said lasted upper to permanently attach said sole thereto.

14. The herein described method for making a cemented shoe consisting in preparing an upper having its bottom edges lasted over an inner sole and cemented thereto and an outer sole unit, comprising an outer sole, a welt permanently attached thereto and a bonding fabric strip permanently attached along its outer edge to the inner edge of said welt, then applying cement to the bottom edges of said lasted upper and to said bonding strip and, finally, while said cement is in a tacky condition, applying pressure to said outer sole to cement said bonding strip to said lasted upper to permanently attach said sole thereto.

15. The herein described method for making a cemented shoe consisting in preparing a lasted upper by lasting the bottom edges of an upper over an inner sole and cementing said edges thereto, preparing an outer sole unit by fastening to an outer sole by a line of lock stitching a welt carrying an inwardly extending bonding strip, said stitching passing through the outer edge of said bonding strip, then applying cement to the lasted edges of said upper and to both sides of said bonding strip, and, finally, while said cement is tacky, positioning said outer sole unit on said upper and applying pressure to said outer sole to cement said bonding strip to the edges of said upper to cause said outer sole to become permanently affixed to said upper.

16. An outer sole unit comprising an outer sole having a welt attached thereto and a bonding strip of fabric arranged within the welt on the inner face of the outer sole and having its outer edge attached to said welt, said bonding strip being adapted for carrying cement for adhesively fastening said outer sole unit to a shoe upper.

17. An outer sole unit comprising an outer sole of rubber or other composition material, a welt

of similar material cemented thereto and a bonding strip arranged on the inner face of said sole within said welt and having its outer edge attached to said welt by a line of stitching, said strip being of a material suitable for carrying adhesive for cementing said bonding strip to a shoe upper to hold said sole affixed thereto.

18. A method of preparing an outer sole unit for adhesive fastening to a lasted upper consisting in providing a sole of suitable material of the exact form and dimension required by the last, then fastening by a line of welt stitching to the inner face of said outer sole around the margin of its forepart a welt provided with an inwardly projecting bonding strip of material adapted for carrying an adhesive, said welt being channeled inwardly from its inner edge parallel with its bottom face and said bonding strip having its outer edge inserted in said channel and secured therein by said line of welt stitching.

19. A method of preparing an outer sole unit for adhesive fastening to a lasted upper consisting in providing a sole of suitable material of the exact form and dimension required by the last, then fastening by a line of welt stitching to the inner face of said outer sole around the margin of its forepart a welt provided with an inwardly projecting bonding strip of material adapted for carrying an adhesive, said welt being recessed on its bottom face inwardly from its inner edge and said bonding strip having its outer edge inserted in said recess and secured therein by said line of welt stitching.

20. A method of making shoes which comprises, lasting an upper, stitching a welt and a fabric fastening strip along the margin of an outsole in a single stitching operation, applying adhesive between said fabric strip and the bottom of said lasted upper, and pressing said outsole against said lasted upper to adhere said strip thereto.

21. A method of making shoes which comprises, lasting an upper with its lasting allowance in flat overlying relation against an insole, temporarily adhesively attaching a fabric fastening strip and a welt, permanently stitching said welt and strip along the margin of an outsole, applying adhesive between said fabric strip and the bottom of said lasted upper, and pressing said outsole against said lasted upper to adhere said strip thereto.

22. A method of attaching an outsole to a lasted upper, which comprises, slitting a welt, attaching a fabric fastening strip in said slit and attaching said welt along the margin of the outsole, applying cement between said strip and the bottom of the lasted upper, and pressing said outsole against said upper to adhere said strip thereto.

23. A method of attaching an outsole to a lasted upper, which comprises, slitting a welt, anchoring a fabric fastening strip in said slit, stitching said welt along the margin of the outsole, applying cement between said strip and the bottom of the lasted upper, and pressing said outsole against said upper to adhere said strip thereto.

24. A method of attaching an outsole to a lasted upper, which comprises, slitting a welt, positioning the outer margin of a fabric fastening strip in said slit, stitching through said welt, strip and the margin of an outsole, applying adhesive between said strip and the bottom of the lasted upper, and pressing said outsole against said upper to adhere said strip thereto.

25. A method of attaching an outsole to a lasted upper, which comprises, slitting a welt, attaching the outer margin of a fabric fastening

strip in said slit with temporary adhesive, sewing said welt along the margin of an outsole with stitches passing through said fastening strip margin, and cementing said strip to the bottom of the lasted upper.

5 26. A shoe bottom unit adapted for cement attachment to a lasted upper, comprising, an outsole, a welt extending along the margin of said outsole, a fabric fastening strip having its outer margin extending beyond the inner edge of said welt, and having its remaining portion extending inwardly over said outsole to provide an upwardly facing cementing surface, and a single row of stitching connecting said welt, strip and outsole.

27. An outer sole unit for a shoe comprising an outer sole member, a welt attached thereto and a bonding strip of fibrous material arranged to extend inwardly of the welt and having its outer edge attached to said welt, said bonding strip having a cementing portion of substantial area extended inwardly in proximity to the inner surface of the sole member to directly overlie the same when the unit is applied to an upper, the upper face of said strip being highly cement-compatible whereby cement applied thereover will directly engage and securely hold the shoe upper imposed thereupon.

WALTER P. FIELD.
